UNITED STATES PATENT OFFICE.

EDWARD B. GIBFORD, OF ADRIAN, MICHIGAN.

DESIGN FOR A RAZOR-STROP.

SPECIFICATION forming part of Design No. 33,943, dated January 22, 1901.

Application filed December 26, 1900. Serial No. 41,173. Term of patent 14 years.

To all whom it may concern:

Be it known that I, EDWARD B. GIBFORD, a citizen of the United States, residing at Adrian, in the county of Lenawee, State of Michigan, have invented and produced a new and original Design for Razor-Strops, of which the following is a specification, reference being had to the accompanying drawings, and to the figures of reference marked thereon, which form a part of this specification.

This invention relates to a design for a razor-strop; and it consists in the configured presentment illustrated in the accompanying drawings, in which—

Figure 1 is a plan view of a razor-strop embodying my design. Fig. 2 is an edge view thereof. Fig. 3 is a transverse section.

The main feature of the design resides in the body portion, having imprinted upon the face thereof a convoluted scroll whose lines

traverse the face of the strop transversely and which extends from end to end thereof.

Referring to the characters of reference, 1 designates the body of the strop, upon the face of which is the imprinted scroll 2, affording a spirally-interwining effect. At the head of the strop is a cap-piece 3, and 4 designates the handle thereof, the whole presenting an ornate and harmonious figure.

Having thus fully set forth my invention, what I claim as new, and desire to secure by Letters Patent, is—

The design for a razor-strop, substantially as herein shown and described.

In testimony whereof I sign this specification in the presence of two witnesses.

EDWARD B. GIBFORD.

Witnesses:

CLARKE E. BALDWIN,
KATE JOHNSTON.
